POLISHING BONNET

Frank Livingston, Worcester, Mass.

Application February 13, 1948, Serial No. 8,110

5 Claims. (Cl. 15—230)

1

The present invention relates to polishing and buffing devices, and more particularly to a polishing or buffing bonnet which is adapted to be removably secured over a rotatable disk of a portable power tool of the type which is commonly employed in the polishing of a variety of articles, such as, for example, furniture and automobile bodies.

The most common type of polishing bonnet employed in the past, and at the present time, comprises a circular-shaped piece of flexible sheepskin or pile fabric which has secured about its peripheral edge a border of plain cloth provided with a draw string. To use such a bonnet or pad, it is positioned over one face of the rotatable disk of a power tool with the hair or pile side of the bonnet exposed. Thereafter, the draw string is tightened and its ends secured together so that the cloth border is drawn about the periphery of the disk thereby to hold the bonnet on the disk. After the power tool is made active, the disk will rotate and carry with it the pad or bonnet which thereafter may be applied to a surface to be polished.

Although literally thousands of the above noted type of polishing bonnets are employed every day in this country in automobile garages, body shops, and furniture plants, the fact is that such a bonnet has a serious drawback in that it has no means whatsoever for either initially centering it upon the tool disk or maintaining it in such a central position in the event that an operator could initially center the same. In this latter connection, it should be realized that in actual use, such a bonnet is rotated by the power tool, and as the rotating bonnet is applied to a surface to be polished, the operator slides the bonnet back and forth over the surface, with the result that the bonnet will tend to shift relative to the tool disk and thus become eccentric with the disk axis, even though the operator was successful in initially centering the bonnet upon the disk.

With the bonnet disposed eccentrically of the disk, the latter element will be in a state of unbalance, thus causing the entire power tool to vibrate when in use. Since such tools are geared to drive the disk and bonnet at about 1400 R. P. M., this vibration becomes very objectionable to an operator, and, in fact, causes operator fatigue.

It is also to be understood that the degree of eccentricity between disk and bonnet many times is so great that a portion of the disk periphery is no longer covered by the sheepskin, but only by the cloth border material and thus, whenever

2

such an exposed portion of the border material engages the surface to be polished, it will be cut, with the result that the surface is marred and the bonnet is rendered completely worthless. In this connection, it is to be appreciated that no sheepskin, or other appropriate bonnet material, is flexible enough to permit its marginal portion to be properly and completely folded about a disk periphery. It is for this reason that a border of plain cloth is employed about the periphery of the bonnet material. Therefore, since it is inevitable that the tool disk will cut the bonnet border, the above described conventional type of bonnet is short-lived. Furthermore, since an operator cannot, with impunity, bring the edge portion of the shifted bonnet against an article to be polished, the use of the bonnet is restricted, for much polishing work is required at the juncture of angled surfaces.

20 In an attempt to rectify the above noted shortcomings, it has become standard practice in many shops to cut a center hole in the bonnet so that the bonnet may be actually clamped upon the tool disk by the disk nut. In other words, the operators first remove the nut which retains the disk upon the tool, and then they apply the bonnet over the disk so that the bonnet hole will receive the shaft upon which the disk is mounted. Thereafter, the nut is threaded over the shaft so as to clamp both the bonnet and disk in position on the tool. With this arrangement, the bonnet is prevented from shifting relative to the disk. However, as soon as the bonnet pile wears, or in the event that excessive pressure is applied to the tool and bonnet, the nut will dig into the work so as to spoil the same. With such an arrangement, the operator can only safely apply less than one half of the bonnet surface to the work to be polished and thus, the time for polishing a surface is greatly increased. Furthermore, the time consumed by an operator in an effort to so center these conventional bonnets upon a disk is appreciable, and thus, costly.

45 It is, therefore, a primary object of the present invention to provide a polishing bonnet of the flexible type which is so constructed that it will not be subject to any of the above noted shortcomings inherent in bonnets heretofore employed.

50 A further object of the present invention is to provide a polishing bonnet which is most efficient in use, but which, at the same time, is inexpensive of manufacture.

55 A more specific object of the present invention is to provide a polishing bonnet which is so con-

structed that it will automatically center itself with respect to a tool disk upon being applied thereto, and remain so centered during the operation of the tool.

With the above and other objects in view, as will hereinafter appear, the invention comprises the devices, combinations, and arrangements of parts hereinafter set forth and illustrated in the accompanying drawings of a preferred embodiment of the invention from which the several features of the invention and the advantages attained thereby will be readily understood by those skilled in the art.

The several features of the present invention will be clearly understood from the following description and accompanying drawings in which,

Fig. 1 represents a perspective view of a power tool to which the present invention is applied.

Fig. 2 represents, on an enlarged scale, a sectional view taken substantially along the line 2—2 of Fig. 1.

Fig. 3 represents, on an enlarged scale, a portion of the device disclosed in Fig. 2.

Fig. 4 represents, on a scale similar to that employed in Fig. 1, the present invention with the draw strings thereof loosened.

Fig. 5 represents a perspective view of a rotatable disk which is adapted to be secured directly to the power tool illustrated in Fig. 1.

Referring particularly to Fig. 1, there is disclosed a common type power tool comprising a motor casing 10 upon the forward portion of which is mounted a combined gear casing and handle member 11. Projecting downwardly from the gear casing 11 is the usual rotatable shaft 12 to which a polishing pad may be applied in a manner as will be hereinafter described. The shaft 12 is driven in the usual manner from an electric motor which is contained within the casing 10. The casing 10 is provided at its other end portion with a handle member 13 which carries a suitable switch 14 by which the motor circuit may be controlled. The circuit wires may be led to the motor through a cable 15 which is shown as extending through the handle 13, all in the usual manner.

Referring to Figs. 1 and 2, the rotatable shaft 12 may be provided at its lower end portion with a flange 16 and a threaded end portion 17 over which a fiber disk 18 may be mounted. A nut 19 may be threaded upon the shaft portion 17 for the purpose of securing the disk 18 rigidly upon the shaft 12. Thus, the disk 18 will rotate with the shaft 12, all in the usual manner.

As hereinabove set forth, it has been the usual practice to secure a polishing bonnet or pad over one face of the disk 18, but difficulties were encountered due to the fact that such prior type polishing bonnets had a tendency to shift relative to the disk 18 thereby becoming eccentric with the axis of the shaft 12. The present invention completely obviates this difficulty.

Referring now to Figs. 2, 3 and 4, a preferred form of the present invention comprises a circular piece of sheepskin 20 having wool or hair fibers 21 projecting from one face portion thereof. Secured to the peripheral portion of the sheepskin or base member 20 is a circular piece of border material 22. Referring particularly to Fig. 3, it is to be understood that in a preferred form of the present invention the border material 22 is folded upon itself and the juxtaposed edge portions 23, 23 thereof are secured directly to the peripheral edge portion 24 of the sheepskin or base member 20 by means of over-edge

stitches 25. By thus securing the free edge portions of the border material to the circular-shaped peripheral edge portion 24 of the sheepskin 20, the border material will be formed as a circular strip, as best disclosed in Fig. 4. The end portions 26, 26 of this border strip are left free so that a draw string 27 may be inserted within the confines thereof. Thus, the pad or bonnet may be applied to the free face of a disk 18 and the border material may be drawn over the peripheral edge portion of the disk by means of the draw string 27. By securing the free end portions of the draw string 27 together in the form of a bow 28, as best illustrated in Fig. 1, the bonnet may be held in place upon the disk 18. However, as hereinabove described, it should be understood that it would be almost impossible for an operator to place such a bonnet exactly centrally on the disk 18, and even if it were located in a central position, the fact remains that the bonnet or pad would shift radially of the disk 18 during its rotation, with the result that the sheepskin or base 20 would be positioned eccentrically of the disk. With such an eccentric condition prevailing, the edge portions of any pad or bonnet, constructed in the conventional manner as thus far described, would have a tendency to dig into a polished surface, thereby marring the same. In order to obviate this shifting to eccentric position, the pad or bonnet of my invention is provided with a relatively stiff binding tape 29. Referring particularly to Figs. 3 and 4, it is to be understood that the binding tape 29 is applied about the juxtaposed edge portions 23 and 24 of the border material and sheepskin 20. This binding tape may be secured to these edge portions by means of a row of stitches 30, and by properly drawing the end portions 31, 31 of the tape together during this stitching operation, it will be understood that the tape will form an annular ring or ridge of material which will project substantially at right angles to the plane of the base material 20.

With the binding tape so applied to the bonnet, it is to be understood that when the bonnet is positioned over the disk 18 in a manner as particularly disclosed in Fig. 2, the tape will function to position the entire bonnet concentrically with the disk 18 and the shaft 12. Thereafter, when the draw string 27 has its ends tightened and secured together, the border material will of necessity be drawn tightly over the binding tape 29 and the periphery of the disk 18 to the end that the outer portions of the tape will be more or less drawn over the periphery of the disk so as effectively to secure the bonnet in its proper position. A polishing bonnet so constructed may be readily applied to a rotatable tool disk and, furthermore, such a bonnet when once properly secured to the disk can never shift so as to be positioned eccentrically of the disk and shaft.

Therefore, the present invention obviates completely the above noted shortcomings that were inherent in those bonnets of the flexible type which have been employed heretofore. It should be also understood that the present invention may be incorporated in any type of bonnet whether the same utilizes a sheepskin or any other type of appropriate base material. Those skilled in the art will further appreciate that the present invention provides a polishing bonnet which is not only efficient in use, but which at the same time is most inexpensive of manufacture.

I claim:

1. A polishing bonnet for a tool having a rotat-

able shaft and a disk secured upon an end portion of the shaft, comprising, a substantially flat circular polishing pad adapted to be positioned over one face of the disk, means in the form of an annular ring formed at the peripheral edge portion of said pad and projecting substantially at right angles from one face of said pad so as to encircle the disk periphery, a strip of border material formed about the peripheral edge portion of said pad at the base of said annular ring and adapted to be drawn over said annular ring and the peripheral edge of said disk, and means associated with said border strip for securing the same about the disk periphery thereby to maintain said pad in concentric position upon the disk.

2. A polishing bonnet for a tool having a rotatable shaft and a disk secured upon an end portion of the shaft, comprising, a flat circular polishing pad of flexible material adapted to be positioned over one face of the disk, means in the form of a relatively stiff annular ring formed at the peripheral edge portion of said pad and projecting substantially at right angles from one face of said pad so as snugly to encircle the disk periphery, a circular strip of border material formed about the peripheral edge portion of said pad at the base of said annular ring, and a draw string attached to said border strip for drawing the free edge portion of the latter about the disk periphery and about said annular ring thereby to maintain said pad in position upon the disk.

3. An article of the class described, comprising, a polishing pad, a strip of border material disposed against the peripheral edge portion of said pad with one edge portion of said border strip being in juxtaposition with the peripheral edge portion of said pad, a binding tape disposed and stitched about the juxtaposed edges of said pad and border strip and having the both end portions of said tape drawn and secured together so that said tape and said juxtaposed pad and strip edges will project substantially at right angles to one face of said pad, and means associated with said strip for drawing the free edge portion thereof over the periphery of said pad and about said binding tape.

4. An article of the class described, comprising, a flat circular polishing pad of flexible material, an elongated strip of border material folded lengthwise of itself with its longitudinal edge portions in juxtaposed relation and positioned in juxtaposition with the peripheral edge portion of said pad, a line of stitches securing the edge portions of said strip to that of said pad, a binding tape disposed and stitched about the circular juxtaposed edges of said pad and border strip and having the both end portions of said tape drawn and secured together so that said tape and said juxtaposed pad and strip edges form an annular ring which projects substantially at right angles from one face of said pad, and a draw string positioned within the interior of said folded strip for drawing the free folded edge portion of said strip over the periphery of said pad and about said binding tape.

5. A polishing bonnet for a tool having a rotatable shaft and a disk secured upon an end portion of the shaft, comprising, a circular polishing pad of flexible material for positioning over one face of the disk, said pad having a substantially flat face portion and a peripheral edge portion, means in the form of a stiff annular ring secured at the peripheral edge portion of said pad and projecting substantially at right angles from the face of said pad so as snugly to encircle the disk periphery, a circular strip of flexible border material secured to said ring, and means carried by said strip of border material for drawing the free edge of the latter over the exposed peripheral edge portion of said disk.
